COMPRESSOR

Walter R. Freeman, Clayton, Mo., assignor to
 Wagner Electric Corporation, St. Louis, Mo., a
 corporation of Delaware

Application December 11, 1942, Serial No. 468,635

12 Claims. (Cl. 230—192)

My invention relates to compressors for placing fluids under pressure and more particularly to compressors of the reciprocating piston type.

One of the objects of my invention is to produce an improved compressor of the type referred to which will compress a fluid more efficiently, will be easier to lubricate, and will operate at cooler temperatures than prior known compressors.

Another object of my invention is to produce a compressor of the reciprocating piston type in which a piston does not perform any compressing operation upon the fluid to be compressed until said fluid has been placed under a super-atmospheric pressure by having its volume added to a volume of fluid already compressed.

Still another object of my invention is to produce an improved reciprocating piston type compressor embodying valve means which will permit a new method of compressing comprising steps whereby a volume of previously compressed fluid and a volume of fluid to be compressed will be connected to each other and allowed to have their pressures equalized and then the total volume will be compressed to the volume which the previously compressed fluid had prior to being connected to the volume of fluid to be compressed.

Yet another object of my invention is to produce a compressor of the reciprocating piston type which will be capable of delivering greater volume of compressed fluid at a lower temperature than prior known compressors having the same piston area and stroke.

Other objects of my invention will become apparent from the following description taken in connection with the accompanying drawings in which Figure 1 is a sectional view of a compressor embodying my invention; Figure 2 is an enlarged view of the piston rod controlled valve mechanism; Figure 3 is a sectional view similar to Figure 1 but showing the pistons and valves in other positions; and Figure 4 is a view of a single piston compressor.

Referring to Figures 1 to 3, my improved compressor comprises a casing 1 having oppositely extending portions 2 and 3 which are provided with cylinders 4 and 5, respectively. The casing between the cylinders is hollow to provide a chamber 6 and journaled in the casing and extending across this chamber is a crankshaft 7.

Cylinder 4 has mounted therein a reciprocable piston 8 connected to the crankshaft by a piston rod 9. Similarly, cylinder 5 has mounted therein a reciprocable piston 10 connected to the crankshaft by a piston rod 11. Both piston rods

are mounted on the same crank arm of the crankshaft and, therefore, as the crankshaft rotates, one piston will be moved inwardly in its cylinder as the other is moved outwardly in its cylinder and vice versa.

The outer end of cylinder 4 has an inlet port 12 for admitting air or other fluid to be compressed to chamber 13 ahead of piston 8. An inlet valve element 14 controls the inlet port and is biased to closed position by a spring 15. The inlet valve element opens only in the direction of chamber 13 and, therefore, air can enter the chamber but is prevented from returning through the port. In a like manner the outer end of cylinder 5 has an inlet port 16 for admitting air to chamber 17 ahead of piston 10. An inlet valve element 18 controls the inlet port and is biased to closed position by spring 19.

As best shown in the enlarged view of Figure 2, piston 8 is provided with a passage 20 through its head which is controlled by a slide valve element 21 cooperating with the inside surface of the head. The opening and closing of the valve element is controlled by a projection 22 on the piston rod which fits in a recess in the element. A leaf spring 23 biases the valve element into engagement with the piston head surface. The piston 10 also has a passage 24 through its head and such is controlled by a slide valve element 25 controlled by a projection 26 on the piston rod. A leaf spring 27 biases the valve against the head surface. The slide valve elements are so arranged as to close the piston head passages when the pistons are at either end of their strokes. If piston 8 is at the inner end of its cylinder and piston 10 at the outer end of its cylinder, as shown in Figure 1, and the crankshaft rotates in a clockwise direction, as indicated by the arrow, then valve element 21 will open and valve element 25 will remain closed as piston 8 moves toward the outer end of its cylinder and piston 10 moves toward the inner end of its cylinder. As piston 10 begins to move toward the outer end, valve element 21 will open quickly as a given angular movement of the crankshaft at this point results in a large angular movement of the piston rod but small piston movement. When piston 8 moves from the outer end toward the inner end of its cylinder and piston 10 moves from the inner end toward the outer end of its cylinder, valve element 23 will remain closed and valve element 25 will be open. Valve element 25 will open quickly at the beginning of the outward movement of piston 10.

Chamber 6 between the cylinders is provided

with an outlet port 28 controlled by a check valve 29. The port communicates with a conduit 30 leading to a storage tank or a device to be operated by the compressed air or other fluid. Oil is placed in the chamber to lubricate the crankshaft, pistons, and other moving parts.

Referring now to the operation of the compressor, valves 21 and 25 will be closed when the pistons are in the positions shown in Figure 1. Air under atmospheric pressure will be in chamber 13 having been drawn in through the inlet port 12 by the movement of piston 8 to the inner end of its cylinder. Previously compressed air is in chamber 6.

As the crankshaft rotates in the direction of the arrow, valve element 21 will be opened at the beginning of the outward movement of piston 8. Valve element 25 will remain closed. When valve element 21 is opened, the air in chamber 6 under pressure will immediately expand and enter chamber 13 ahead of the piston. The pressures will immediately equalize. The previously compressed air will thus have additional quantity of air added to it. As pistons 8 and 10 now continue to move to the left, the air in the intercommunicating chambers 6 and 13 will be compressed by piston 10. Figure 3 shows the positions of the parts of the compressor as the compressing takes place. After the pressures of air in chambers 6 and 13 equalize and piston 8 continues to move to the left, the air in chamber 13 will be transferred through the open passage 20. Piston 8 will do no compressing due to the open condition of the passage. During the movement of piston 10 to the left, air at atmospheric pressure will be drawn into chamber 17 through the inlet port 16.

When pistons 8 and 10 reach the left end of their cylinders, valve element 25 will still be closed and the valve element 21 will become closed. The volume of compressed air will be the same but since it has had added to it a volume of air (that of chamber 13 when piston 8 was at the left end of its cylinder) the pressure will be increased and some of it will cause an increase in the pressure of the air in the storage tank by flowing out through the outlet of chamber 6.

As pistons 8 and 10 now move to the right by continued rotation of the crankshaft, valve element 21 will remain closed and valve element 25 will open. The compressed air in chamber 6 will now flow into chamber 17 filled with un-compressed air and the air in both chambers will have the same pressure. This volume of air will now be compressed by piston 8 moving to the right, thus raising the pressure of the air in chamber 6. During the movement of piston 8 to the right, air under atmospheric pressure will be drawn into chamber 13 and be ready to be added to the previously compressed air as the cycle of operation is repeated.

From the operation of the compressor just described, it will be apparent that the compressing operation takes place in a body of air in a large chamber 6. The heat resulting from the compression of the air will thus be able to be dissipated over a larger surface and, therefore, the outlet temperature of the compressed air will be cooler than that of a compressor of the conventional reciprocating type in which the air is compressed by the head of a piston travelling to the end of a cylinder having an outlet therein. The compressor will also be very efficient because substantially all of the air drawn into chambers 13 and 17 to be compressed will be added

to the previously compressed air and placed under pressure. The clearance between the piston at the end of its stroke and the cylinder can be very small. This will permit very little air under pressure to be lost when the piston moves away from the cylinder head and air at atmospheric pressure is drawn in. Also, this lost air under pressure will not be under as great a pressure as would be the case where the compressing took place between the piston head and cylinder head as in prior compressors. It is also to be noted that since compressing does not take place in chambers 13 and 17, these chambers will be cooler and, therefore, there will be less expansion of the air as it is drawn in from the atmosphere. By keeping the air to be compressed cool, it will have a greater density and consequently less work will be necessary to compress it to a predetermined pressure. Another feature to be noted from the method of compressing the fluid is that the entire stroke of the piston is employed only to increase the pressure of the previously compressed air to the final pressure and not to raise the pressure of air from atmosphere to the final pressure as in the conventional method of compressing. The work done is the same due to the different volumes compressed but such work is more evenly distributed throughout the stroke of the piston instead of being concentrated mostly at the end of the stroke. Tests have shown that the improved compressor will compress more air with the same amount of work than known reciprocating piston type compressors having the same size piston and the same piston stroke. Although only two compressing pistons are shown, a greater number can be employed without changing the method of compressing.

The compressor will be lubricated by the oil in chamber 6 being splashed about by the crank-shaft. No bad carbonization of this oil will occur on the heads of the pistons and the heads of the cylinder since compressing is not done therebetween and, therefore, no high temperatures at such localities to cause carbonization. The pistons also will not be directly forcing oil laden air out of the compressor. Any oil laden air that gets into chambers 13 and 17 will return to chamber 6 when the pistons move to the outer ends of the cylinders. Any oil laden air that passes the outlet port 28 can be passed through an oil separator and the separated oil returned to chamber 6. It is thus seen that very little oil will be lost and particularly very little by carbonization. The pistons will also be better lubricated because of less destruction of the oil in the cylinder heads. It is also to be noted that by substantially eliminating carbonization or "caking" of oil on the piston heads and cylinder heads, no added clearance therebetween need be allowed which, as already noted, results in increased efficiency not possible in prior known compressors of the reciprocating piston type.

A compressor in which only the single piston 8 is employed is shown in Figure 4. All the parts are the same as previously described in connection with Figures 1, 2, and 3 except cylinder 5, piston 10, and the parts associated therewith are eliminated. The single piston and cylinder, and the valves shown are all designated by the same reference characters as employed to designate the same parts in Figures 1, 2, and 3. When a single piston is employed the compressing of the body of un-compressed air added to the previously compressed air takes place during the inward stroke

of the piston. There will be no compressing during the outward stroke of the single piston as is done in the two piston compressor where the eliminated second piston acted on the added new body of air.

Being aware of the possibility of modifications in the particular structure herein described without departing from the fundamental principles of my invention, I do not intend that its scope be limited except as set forth by the appended claims.

Having fully described my invention, what I claim as new and desire to secure by Letters Patent of the United States is:

1. In a compressor, two chambers, a movable wall between the chambers, means comprising a valve for placing the chambers in communication with each other, positive means for so coordinating the operation of the valve and the movement of the movable wall that when the wall moves in one direction the valve will be closed to thereby permit the wall to compress the fluid in the chamber the volume of which is being decreased by the wall movement and when the wall moves in the opposite direction the valve will be opened and maintained in an open condition throughout the movement in said opposite direction to permit the fluid in the chambers to interchange and assume equal pressures without any appreciable compressing action by the wall during said opposite direction movement, and means for permitting fluid to be compressed to enter the chamber which is having its volume increased during the compressing movement of the wall.

2. In a compressor, two chambers divided by a movable wall, means for moving said wall to vary the volumes of the chambers, valve means permitting fluid which is to be compressed to enter one chamber only when the wall is moved to decrease the volume of the other chamber, means comprising valve means under the control of the wall moving means for placing the chambers in communication with each other irrespective of any difference in pressure when the wall is moved to decrease the volume of the chamber to which fluid is to be compressed has been admitted, and means for compressing the fluid in both chambers when they are in communication with each other.

3. In a compressor, a cylinder, a piston therein, means for reciprocating the piston, means forming chambers on each side of the piston, means for permitting fluid which is to be compressed to enter the chamber on one side of the piston during its stroke to increase the volume of said one chamber, and means comprising valve means under the control of the piston reciprocating means for placing the chambers in communication with each other only during the return stroke of the piston.

4. In a compressor, a cylinder, a piston therein, means for reciprocating the piston, means forming chambers on each side of the piston, means for permitting fluid to be compressed to enter the chamber on one side of the piston during its stroke to increase the volume of said one chamber, valve means for placing the chambers in communication with each other, and means for causing said valve means to be actuated to an open position by the piston reciprocating means and to remain in open position only during the return stroke of the piston.

5. In a compressor, a cylinder, a piston therein, means comprising a crank and piston rod for

reciprocating the piston, means forming chambers on each side of the piston, means for permitting fluid to be compressed to enter the chamber on one side of the piston during its stroke to increase the volume of said one chamber, a passage between the chambers, a valve for closing the passage, and positive means operable by the piston rod when being moved to cause a return stroke of the piston for holding said valve in open position.

6. In a compressor, a compressing chamber and two other chambers, two movable members one of which forms a movable wall between one of said two chambers and the compressing chamber and the other of which forms a movable wall between the other of said two chambers and the compressing chamber, means for moving said members simultaneously so that one of the two chambers will increase in volume while the other decreases and vice versa, an inlet check valve for each of said two chambers, means comprising a valve associated with each of the two chambers for placing each of said two chambers in communication with the compressing chamber, and means for positively controlling the opening and closing of each valve by the moving means for the members, each valve being open only during the period in which the movable member of the chamber with which it is associated is being moved to decrease the volume thereof.

7. In a compressor, two cylinders each communicating with a common compressing chamber at one of its ends, pistons in the cylinders, means for reciprocating the pistons so that one moves toward its cylinder head while the other moves away from its cylinder head, inlet valves for admitting fluid to the head portions of the cylinders as the pistons move away from said head portions, and means comprising valves positively controlled by the reciprocating means for permitting the head portion of each cylinder to communicate with the compressing chamber during the movement of the piston therein toward the cylinder head irrespective of any differences in pressure and for preventing said communication during the stroke of said piston in the opposite direction.

8. In a compressor, two cylinders, pistons reciprocable therein, a crank shaft and piston rods for reciprocating the pistons simultaneously in opposite directions in the cylinders, a common chamber communicating with an end of each cylinder, an inlet valve for each cylinder for admitting fluid to be compressed to the cylinder ahead of the piston therein during movement of the piston toward the end communicating with the common chamber, means comprising a valve for placing the portion of a cylinder ahead of the piston therein in communication with the common chamber, and means positively operable by the piston rods for opening the last named valves, each valve being open only when its operating piston rod moves the piston in the cylinder with which it is associated in a direction to decrease the volume of the portion of the cylinder ahead of the piston.

9. In a compressor, two chambers divided by a movable wall, means for moving said wall to vary the volumes of the chambers, an inlet for one chamber, a valve for permitting fluid to enter the inlet only as the volume of the one chamber is increased by movement of the wall, a passage between the chambers, a valve for said passage which when open permits flow of fluid

between the chambers in both directions and when closed prevents flow of fluid to the chamber having an inlet, and means positively operable by the wall moving means for opening the passage valve only when the volume of said one chamber is decreased by movement of the wall.

10. In a compressor, a non-compressing chamber, a compressing chamber, a separating movable wall between the chambers, means for moving said wall to vary the volumes of the chambers, an inlet to the non-compressing chamber, a valve for the inlet permitting fluid to be compressed to enter the non-compressing chamber only when the volume of said chamber is increased, a passage permitting communication between the chambers, a valve for controlling said passage, and means positively controlled by the wall moving means for causing said last named valve to be open irrespective of any difference in pressure to permit flow of fluid through the passage in both directions when the movable wall is moved to decrease the volume of the non-compressing chamber and increase the volume of the compressing chamber whereby the pressures of the fluid in both chambers will equalize and for causing said last named valve to be closed to prevent flow of fluid from the compressing chamber to the non-compressing chamber when the movable wall is moved to cause increase in

volume of the non-compressing chamber and decrease of volume of the compressing chamber.

11. In a compressor, a cylinder, a piston in the cylinder, means for reciprocating the piston, a compression chamber at the rear of the piston, an inlet for the cylinder ahead of the piston, a check valve for the inlet, a passage through the piston, a closure valve for the passage, and means positively controlled by the reciprocating means and operable when the piston is moved forwardly in the cylinder for opening the closure valve to permit interchange of fluid in both directions between the portion of the cylinder ahead of the piston and the compression chamber at the rear thereof.

12. In a compressor, a cylinder, a piston in the cylinder, means for reciprocating the piston comprising a crank and piston rod, a compression chamber at the rear of the piston, an inlet for the cylinder ahead of the piston, a check valve for the inlet, a passage through the piston, a closure valve for the passage, and means positively controlled by the crank and piston rod during forward movement of the piston for maintaining the valve open to permit interchange of fluid in both directions between the cylinder ahead of the piston and the compression chamber at the rear thereof.

WALTER R. FREEMAN.
